EDWARD B. VALOT, OF LEES SUMMIT, MISSOURI.

LIQUID-FUEL BURNER.

1,059,425.

Specification of Letters Patent. Patented Apr. 22, 1913.

Application filed May 28, 1912. Serial No. 700,239.

To all whom it may concern:

Be it known that I, GEORGE R. BAIR, a citizen of the United States, residing at Lees Summit, in the county of Jackson and State of Missouri, have invented a new and useful Liquid-Fuel Burner, of which the following is a specification.

This invention has reference to improvements in liquid fuel burners, and its object to provide a means for the efficient combustion of liquid fuel.

In accordance with the present invention there is provided a water receptacle with means for maintaining a substantially constant level of water therein, and this receptacle has introduced therein a nozzle carrier directed toward the water in the receptacle with the feed pipe to the nozzle passing through the water within the receptacle and receiving liquid fuel from a suitable source usually contained in a tank provided with means for causing air pressure therein. The jet of fuel is directed toward the water so that the burning fuel strikes the water and vaporizes the latter and the mixed fuel and vaporized water cause a smokeless flame to issue from the burner, the vaporized water being heated to such a degree as to be decomposed and therefore on reunion of its components produces an intensely hot flame.

The invention will be best understood from a consideration of the following detailed description taken in connection with the accompanying drawings forming a part of this specification, with the further understanding that while the drawings show forms of the burner which in practice prove efficient, the invention may assume other practical forms embracing the same salient features as the forms illustrated, wherefore the invention is not limited to any exact conformity with the showing of the drawings.

In the drawings:—Figure 1 is a vertical section through a burner constructed in accordance with the present invention with some parts shown in elevation, and a stove or closure for the burner indicated in dotted lines. Fig. 2 is a longitudinal section on a larger scale than Fig. 1 of a jet device employed when gasoline or the like is the fuel. Fig. 3 is an end view of the device of Fig. 2. Fig. 4 is a view similar

to Fig. 2 but illustrating the form of nozzle employed when kerosene or like fuel is used. Fig. 5 is an end view of the structure of Fig. 4.

Referring to the drawings, there is shown in Fig. 1 a casing 1 which may be taken as indicative of any stove structure or enclosure for the burner, and while no attempt is made to show any particular structure of stove, it will be understood that the structure is such as to permit the use of a burner of the present invention. In the particular showing of Fig. 1 two cylindrical members 2—2 are indicated, but it will be understood that this constitutes a double burner, and that so far as the structure is concerned a single cylindrical member 2 may be used, or more than two may be used. Each cylindrical member 2 has a closed bottom 3 and is open at the top, as indicated at 4, it being understood that in practice the cylindrical members are placed upright. These members are located within the stove 1 and are suitably separated, and considering that there are two members 2, they are connected together by a pipe 5 at a short distance above the bottom 3, this being a free connection, so that if water, indicated at 6, be introduced into one member 2 it will flow into the other member 2 until at the same level. Extending from one of the members 2 is a pipe 7 which may be at the same level as the pipe 5, although this is not mandatory. The pipe 7 extends to the exterior of the stove body 1 and enters a tank 8 below the upper end thereof, which upper end may be open. The tank 8 receives a bell 9 having a filling opening normally closed by a plug 10, and near the bottom the bell 9 is provided with an orifice 11. If it be assumed that the bell 9 is filled with water, such water will find its way out through the orifice 11 into the tank 8 until the level of water within the tank 8 is high enough to cover the orifice, and further escape of water is then prevented. By suitably placing the tank 8, the level of water therewithin will determine the level of water within the cylindrical members 2.

Entering each cylindrical member 2 through the bottom 3 is a pipe 12 which may be carried up through the water 6 to near the top of the member 2, and then di-

rected downwardly and at its end is provided with an externally screw-threaded portion 13 adapted to receive a nipple 14 or 15 as the case may be. Each pipe 12 is provided with a controlling valve 16, and the valves are in turn connected to a common supply pipe 17 coming from a closed tank 18 containing the supply of fuel. This tank may be provided with a pump 19 for establishing air pressure therein, and a gage 20 for indicating the pressure, while fuel may be placed in the tank through an opening normally closed by a plug 21. The nipple 14 is shown as provided with a single escape orifice 22, while the nipple 15, which is laterally expanded, as shown, is provided with numerous escape orifices 23.

It will be understood, of course, that where but a single burner made up of the cylindrical member 2 and the parts contained therein, is employed, the pipe 17 will connect directly to the valve 16 for said burner and where more than two burners are employed a corresponding number of valves may be connected to the supply pipe, but whatever be the number of burners, a single water supply tank 8 with its reservoir 9 will be sufficient.

The nipple 14 having a single orifice or passage 22 is employed when gasoline is the fuel, and the nipple head 15 with numerous orifices 23 is employed when kerosene or like material is the fuel, it being found advisable to cover a greater area with the fuel in the latter case than where gasoline is employed.

If it be assumed that a suitable pressure has been established within the tank or reservoir 18 and that a suitable amount of water has been placed in the bell or supply member 9 and has filled the cylinders 2 up to the desired level, above which these cylinders may have orifices 24, then on opening the valve or valves 16 fuel will flow to the jet nipple and may be there lighted and the flame so caused is directed against the water, the combustion being effected by air entering through the orifice 24. The flame will quickly convert the water into steam and superheat the steam, so that it tends to augment the supply of oxygen and the steam is separated into its component parts which will reunite for the production of an intensely hot flame, wherein all particles of carbon are thoroughly burned and a smokeless flame results. As the water within the members or burners 2 is evaporated the supply within the tank 8 is drawn open and ultimately the level within said tank sinks sufficiently for the entrance of air through the orifice 11 and water is thereby permitted to flow from the bell 9 into the tank 8 to raise the level to its original point. This action is entirely automatic, so that for all practical purposes the level of water within the burners 2 is maintained practically con-

stant and the action of the burners continues indefinitely to be controlled at will by a manipulation of the valves 16 and the maintenance of sufficient pressure within the tank 18 by the pump 19.

It is to be noted that the vaporization of the water is due to the direct contact with the surface of a body of water of the flame and that the vapor thereupon rises into enveloping relation with the flame to be further acted thereupon and to ultimately augment the energy of the flame as it issues from the open end of the burner cylinder or casing. There are no vaporizing pipes or spraying jets to become clogged up and furthermore the fuel supply pipe is carried through the body of water so that the fuel supply at no time becomes unduly heated before reaching the jet end of the burner pipe, and consequently there is no deposition of carbon or superheating of the fuel before it issues from the jet.

What is claimed is:—

1. A burner for liquid fuel comprising a casing open at the upper end and closed at the lower end, means for supplying water to the casing and maintaining it therein at a predetermined level and a supply pipe for fuel entering the chamber upwardly from the bottom thereof and terminating above the predetermined level for the water in a jet member directed toward said water level, the upper end of the water container being open.

2. A liquid fuel burner comprising a receptacle open at one end and closed at the other end, means for maintaining water therein at a predetermined level, said receptacle having air orifices at a higher level than the predetermined level to which water is to be filled into the receptacle, and a supply pipe for fuel entering through the closed bottom of the receptacle and rising to a point near the open end of the receptacle and there directed toward the closed end of the vessel and provided with a jet device for directing a flame of burning fuel toward and against the body of water when present in the receptacle.

3. A burner for liquid fuel comprising a cylindrical member having a closed lower end and an open upper end and above the lower end provided with air inlets, a pipe connected to the cylindrical member below the air inlets, a constant-level supply tank connected to the pipe for maintaining water in the cylindrical member at a predetermined level below the air inlets, and a supply pipe for fuel entering the closed end of the cylindrical member and rising in said member to a higher level than that to which the water is to be maintained, the fuel supply pipe terminating in a jet device directed toward the closed end of the receptacle.

4. A means for burning liquid fuel com-

prising a pressure tank for the fuel, a valved pipe leading therefrom, a burner casing having a closed lower end and an open upper end with the valved supply pipe entering 5 the casing through the closed lower end and extending through said casing to near the open end thereof and there returned upon itself and provided with a jet member for directing a flame toward the closed lower 10 end of the casing, and a constant-level water supply means for the burner casing communicating therewith near the bottom thereof, said constant-level water supply means comprising a tank having a water 15 container therein closed at the upper end and provided with an orifice at the lower end opening into the water tank to maintain a constant water level therein, the burner casing having air inlets thereto at a higher 20 point than that attained by water admitted

to the casing from the constant level water supply means.

5. A burner for liquid fuel comprising a casing open at the upper end, means for supplying water to the casing to a predetermined level, and a supply pipe for fuel terminating in a jet member directed toward the bottom of the casing and located above the predetermined water level in position to direct a flame issuing from the jet member 25 against the surface of a body of water when present in the casing.

In testimony, that I claim the foregoing as my own, I have hereto affixed my signature in the presence of two witnesses.

GEORGE R. BAIR.
